United States Patent Office.

WILLIAM BRAIDWOOD AND HORATIO JONES HEWITT, OF NEW YORK, N. Y.

Letters Patent No. 103,972, dated June 7, 1870.

IMPROVEMENT IN WATER-WHEELS.

The Schedule referred to in these Letters Patent and making part of the same.

To all whom it may concern:

Be it known that we, WILLIAM BRAIDWOOD and HORATIO JONES HEWITT, both of the city, county, and State of New York, have invented a new and improved Water-wheel; and we do hereby declare the following to be a full, clear, and exact description thereof, which will enable those skilled in the art to make and use the same, reference being had to the accompanying drawing forming part of this specification, in which drawing—

Figure 1 represents a vertical section of this invention.

Figure 2 is a plan or top view of the same.

Similar letters indicate corresponding parts.

This invention relates to a water-wheel, the pen-stock of which covers one-half or less of the periphery and sides of the wheel, fitting closely to the same, in such a manner that the water, after having acted on those buckets of the wheel which are in the interior of the pen-stock, is free to discharge, and all backlash and undue friction of the water in discharging is avoided.

In the interior of the pen-stock are arranged a series of bridges, the lower edges of which extend down close to the periphery of the wheel, while their upper edges come close to the gate in such a manner that the stream passing through the pen-stock can be concentrated and made to act on a greater or smaller portion of the wheel.

In the drawing—

The letter A represents a pen-stock, which is provided with segmental flanges, *a b*, fitting the periphery of the wheel, and, with two cheek-pieces *c*, fitting the sides of the wheel, and forming, in connection with the flanges *a b*, a case, inclosing one-half of the wheel, or less, and leaving the back of said wheel entirely open, as shown in the drawing.

The cheek-pieces *c* form the bearings for the shaft

d, on which the wheel *B* is mounted, and this wheel is constructed with straight buckets, as shown, or it may be made with curved buckets, as experience may dictate.

In the interior of the pen-stock *A* are a series of stationary bridges or partitions, *e*, the lower edges of which come close to the periphery of the wheel, while their upper edges extend under the gate *f*, so that in opening the gate the stream can be admitted to one or more of the channels formed between the bridges, and, consequently, when the water is low, the stream can be concentrated and brought to act in a compact mass upon the wheel.

To prevent the stream, when thus concentrated, from spreading over the entire width of the wheel, said wheel is provided with one or more permanent annular partitions, *g*, dividing off the spaces between the buckets in compartments corresponding to the compartments between the bridges in the pen-stock.

By these means a wheel is obtained on which the water acts with its full force, and which allows the water to discharge quite freely, and with the least possible obstruction or loss of power.

What we claim as new, and desire to secure by Letters Patent, is—

1. The pen-stock *A*, provided with segmental flanges *a b*, and cheek-pieces *c*, forming a case which incloses one-half of the wheel, or less, leaving the other half entirely open, as set forth.

2. The bridges *e* in the pen-stock, in combination with the gate *f* and wheel *B*, as described.

WILLIAM BRAIDWOOD,
HORATIO JONES HEWITT.
